UNITED STATES PATENT OFFICE.

THOMAS F. CONNOR, OF DECORAH, IOWA.

WRENCH.

1,391,461.

Specification of Letters Patent. Patented Sept. 20, 1921.

Application filed February 3, 1919. Serial No. 274,768.

To all whom it may concern:

Be it known that I, THOMAS F. CONNOR, a citizen of the United States, residing at Decorah, in the county of Winneshiek and State of Iowa, have invented certain new and useful Improvements in Wrenches, of which the following is a description.

My invention belongs to that general class of devices known as wrenches and relates particularly to a wrench which may be quickly and easily applied or removed. The invention has among its objects the production of a device of the kind described that is simple, efficient, durable and satisfactory for use wherever found applicable. Many other objects and advantages of the construction herein shown and described will be obvious to those skilled in the art from the disclosures herein given.

To this end my invention consists in the novel construction, arrangement and combination of parts herein shown and described, and more particularly pointed out in the claim.

In the drawings, wherein like reference characters indicate like or corresponding parts,

Figure 1 is a side elevation of one form of my wrench;

Fig. 2 is a sectional view through the same;

Fig. 3 is a sectional view taken substantially on line 3—3 of Fig. 1;

Fig. 4 is a sectional view taken substantially on line 4—4 of Fig. 1;

Fig. 5 is a sectional view similar to Fig. 3, showing the parts in changed position;

Fig. 6 is a perspective view of the member 8;

Fig. 7 is a sectional view of a modified construction;

Fig. 8 is a sectional view taken substantially on line 8—8 of Fig. 7;

Fig. 9 is a side elevation of another form of wrench;

Fig. 10 is a sectional view taken substantially on line 10—10 of Fig. 9; and

Fig. 11 is a sectional view taken substantially on line 11—11 of Fig. 9.

Referring to the drawings, Figs. 1 to 6 represent an ordinary wrench, in which 1 is a suitable shank provided with a head or engaging jaw 2, the shank being extended as at 3 the desired length to provide a handle.

The same is also preferably threaded at one edge 4 to form a cog-rack, and may be pro-

vided with a stop pin 5 or equivalent, the purpose of which will be hereafter referred to. Mounted on the shank 1 is a slidingly movable member 6 having a co-operating jaw 7. Also arranged on the shank and movable with the head 6, is what may be termed a nut or sleeve 8, which is threaded as at 9 to engage with the threads 4. A groove or threadless part 10, however, is formed on the interior of the nut so that when the nut is turned substantially as shown in Fig. 5, the groove and cog-rack are brought into registry, the part may readily slide along the shaft 3 free from the restrictions of the nut. I have shown filler blocks 11, threaded to engage the interior thread 9, these maintaining the nut in place and sliding freely when the nut is moving on the shank. The nut or sleeve 8 is shown provided with a circumferential groove 12 which is arranged to be engaged by an engaging member 13 on the head 6, the same permitting the rotation of the nut, but causing the head to slide with the nut when turned or moved on the shank. A stop pin 14 is also shown which will limit the movement of the nut so that the groove 10 may be brought to register with the threads 4 when desired, so that the registration may be brought about quickly and without inconvenience.

The construction shown in Fig. 7 is very similar, except that on the shank 21 having head 22 is arranged a head 16 provided with extending portions 17. A block 18 is shown, and the parts secured together by rivets 18 or equivalent means. A jaw member 19 in this case is provided, the same being adjustably secured in place by a bolt, screw, rivet 95 or the equivalent 20, permitting the same to oscillate slightly. In this case the jaws are preferably formed with engaging teeth or serrations 26 and 27. A nut 28 similar to the nut 8 is provided on the shank 23 and arranged to engage with the threads 24, 25 being a stop pin for limiting the movement of the head and nut. In this case nut 28 is provided with a groove 30 and groove 32, and the extending end of member 18 is provided with a groove engaging lug 33. A pin similar to pin 14 and filler blocks 34 corresponding to blocks 11 are also provided.

A simplified construction of the wrench is shown in Figs. 9, 10 and 11, in which 39 represents a shank provided with a jaw

40, a movable member 36 having a jaw 44 being mounted on the shank. The shank 39 is extended as at 41 and threaded as at 42 to engage with the nut 38 which is internally threaded, and provided with the groove 45. In this case the head 36 is extended as at 37 and provided with threads 46. When the nut is turned and engages with the threads 42, the head 36 is locked 10 against movement.

With all of the constructions illustrated and described, the head carrying one of the movable jaws may be shifted on the shank to bring the jaws the desired distance apart, 15 after which the nut 8, 28 or 38, as the case may be, is given a turn, locking the head against movement so that the jaws will perform their function. The device is exceedingly simple, consists of a minimum of 20 parts, is extremely durable and will not easily get out of order. The same may be manufactured at comparatively small cost. The saving in time in adjusting the head will amount to considerable, and is of no 25 small importance at the present time where there is a shortage of labor and every possible minute should be utilized.

Having thus described my invention, it is obvious that various immaterial modifications may be made in the same without departing from the spirit of my invention; hence I do not wish to be understood as limiting myself to the exact form, construction, arrangement and combination of 30

parts herein shown and described or uses 35 mentioned.

What I claim is:

A device of the kind described, comprising a substantially flat shank having a cog rack formed upon one edge thereof and carrying upon one end a transversely extending jaw, in combination with a part slidably mounted upon said shank and extended on one side thereof, said last mentioned part having an open slot therein, an oscillating coöperating jaw mounted in said slot in the extended portion of the slidable member, a rotatable screw-threaded nut to control the movement of the slidable member upon the shank, said slidable member being provided with a rearward extension adapted to loosely engage in said rotatable nut, filler blocks arranged within the rotatable nut on the flat sides of the shank, said nut having formed therein a threadless part adapted to be brought into registry with said cog racks, whereby the nut, filler blocks and slidable member may be slid on said shank, and a stop limiting said sliding movement away from said fixed jaw. 55

In testimony whereof I have hereunto signed my name in the presence of two subscribing witnesses.

THOMAS F. CONNOR.
